VAPOR GENERATOR

William M. Firshing, West New Brighton, Staten Island, N. Y., assignor to The Babcock & Wilcox Company, Newark, N. J., a corporation of New Jersey

Application April 13, 1935, Serial No. 16,123

3 Claims. (Cl. 122—327)

This invention relates to boilers and more particularly to water tube boilers of the type embodying a steam and water drum disposed above the furnace chamber and connected by sets of downwardly extending tubes with two water drums, one on each side of the combustion chamber, the arrangement being such that the gases from the furnace chamber pass divergently right and left through the respective sets of 10 water tubes to a suitable uptake or uptakes.

The objects of my invention are comprised in the provision of a water tube boiler of the above type which is highly compact, one which is light in weight for a given capacity, one which is so 15 designed as to make possible a maximum of combustion chamber space, one which is of a strong and durable construction, and lastly, one which is highly efficient in operation.

These and other objects are effected by my invention, as will be apparent from an examination of the following description and claims, taken in connection with the accompanying drawings, in which:

Fig. 1 is a transverse, vertical, sectional view 25 through a boiler constructed in accordance with the present invention;

Fig. 2 is an enlarged fragmentary sectional view illustrating the detail arrangement of a portion of a set of steam generating tubes, the view being 30 taken on the line 2—2 of Fig. 1; and

Fig. 3 is a view similar to Fig. 1 and illustrates a modified form of my invention.

It will be recognized as the description proceeds that my improvement is especially applicable to boilers used for the generation of steam on shipboard; however, it is to be understood that in so far as certain of the broader aspects of my invention are concerned, my improved form of water tube boiler may be used for the generation 40 of steam wherever desired.

Referring now in detail to the construction illustrated and particularly to the modification shown in Figs. 1 and 2 of the drawings, the reference numeral 10 indicates a combustion chamber wherein a suitable fuel, for example, oil is burned. The burners for projecting the oil and combustion supporting air into the chamber 10 are indicated at 11 as extending through an end wall of the chamber.

50 My improved boiler comprises an upper steam and water drum 12 disposed above the combustion chamber 10 and a pair of lower water drums 13 and 14 extending in the same general direction as the drum 12 and arranged at 55 opposite sides of the combustion chamber, as in-

dicated. Each of the lower water drums 13 and 14 is connected to the upper steam and water drum 12 by a separate set of steam generating tubes 15. The hot gases resulting from combustion of the fuel in the chamber 10 rise from the latter and divide, one part flowing to the right and traversing one of the sets of tubes 15 and the other part flowing to the left and traversing the other set of tubes. In traversing the sets of tubes 15 the major portion of the heat therefrom 10 is given up to the water within the tubes. The gases pass out of the furnace chamber through suitable gas outlets 16 and 17 respectively.

The boiler shown in the accompanying drawings is particularly useful in marine applications and, to this end, is supported at its bottom by suitable structural members 18 which support the water drums 13 and 14 through saddles 19 and 20 respectively, secured to the water drums. The upper steam and water drum 12 is supported 20 from the lower water drums 13 and 14 by the two sets of tubes 15. In marine installations it is particularly desirable to support the boilers from the bottom as headroom is at a premium and as the ship frames are in the bottom.

As will be observed from an examination of Fig. 1, I have shown each set of steam generating tubes 15 as being divided into a plurality of groups, there being three groups to each set, the groups being indicated by the reference numerals 21, 22 and 23 respectively.

In order to provide the necessary strength for supporting the upper steam and water drum 12 from the lower water drums 13 and 14, the groups 21 which are adjacent the combustion chamber 35 are made straight for practically their entire length, except for their terminal portions 24 thereof, which are curved to provide radial entrances into their respective drums so as to assure good tube seats and the desired characteristics of lightness and strength in the drums and ease of manufacture. The furnace volume is the largest possible consistent with the strength derived from the straight tubes and contributes to light weight for a given steaming capacity by 45 permitting large quantities of fuel to be burned per unit of tube surface with a strong structure.

The tubes forming the groups 22 are similarly bowed away from the combustion chamber to permit expansion and contraction thereof due 50 to temperature changes and also for the purpose of providing the maximum heat absorbing surface, the curved tubes being longer than the straight tubes. The tubes forming the groups 23 at the outside of the sets of tubes are also simi- 55

larly bowed away from the combustion chamber for the same reason as just explained in connection with the groups 22.

With the improved design of the three drum boiler furnace shown, it is possible to provide an 8% larger combustion chamber space, to burn a correspondingly greater amount of fuel, and to generate a correspondingly greater amount of steam per hour than is possible with the conventional boiler furnace of this type having the same arrangement and spacing of drums, but having the first groups of tubes curved or bowed toward the combustion chamber. As stated, the enlarged combustion chamber space and greater fuel burning capacity is made possible by the provision of straight tubes adjacent the furnace chamber, and the larger steam generating rate is aided by the large heat absorbing surface of the curved or bowed groups of tubes 22 and 23. The curved tubes occupy space which is necessarily present, but not ordinarily used in the conventional boiler. Hence, my improved boiler furnace does not require any more room in the ship than the conventional construction, just referred to, yet my furnace is capable of burning more fuel and hence of generating more steam for a given heat absorbing surface.

In each instance, the terminal portions of the curved or bowed tubes in the groups 22 and 23 are bent to provide the desired radial entrances into their respective drums. The groups 22 and 23 are so constructed and arranged with respect to each other and to the groups 21 as to provide spaces 25 and 26 between adjacent groups, the purpose of these spaces is to permit the installation of soot blowers, indicated at 27, which provide for the quick and effective cleaning of the highly compact boiler disclosed. Baffles 29 serve to equalize the gas flow, particularly through the loosely spaced rear groups 23 of tubes.

In order to provide for the maximum heat absorbing surface for a given weight of boiler, all of the tubes with the exception of those tubes which are immediately adjacent and delineate the upper portions of the combustion chamber are relatively small in diameter, the latter being relatively large in diameter, as will be presently explained. High efficiency is essential in the interest of reduction of weight of fuel that must be carried by the ship as well as cost of operation. High efficiency means a large fraction of the heat of the fuel absorbed by the water in the tubes within an allowable limit of draft loss or gas-flow resistance across the tube bank imposed by the capacity. High efficiency is promoted in the construction described by the provision of a large number of small diameter tubes across the sets and by the provision of the maximum length of tubes so as to give a large heat absorbing surface.

As stated above, those tubes of the groups 21 which delineate or flank the combustion chamber are of larger diameter than the remaining tubes. The relatively larger tubes are indicated by the reference numeral 28 and in the construction illustrated comprise the first two rows of tubes considered in the direction of gas flow. The tubes 28 are made relatively larger so as to assure presence of water at all times in that portion of the boiler which is exposed directly to the radiant heat of combustion and, at the same time, so as to provide the necessary supporting strength for the upper steam and water drum.

It is essential that all of the tubes be protected against overheating which will result if the tubes

develop dry spots, because such overheating will soften the metal and cause the tubes to burst. This is particularly true of the straight tubes in the groups 21, including the tubes 28, as overheating will also impair their strength necessary to support the drum 12. The tubes are protected from overheating by the water therein; but the generation of steam reduces the water content toward the top and tends to produce dry spots, and this tendency varies inversely with the diameter of the tube for a given length and directly with the degree to which the tube is heated. It is, therefore, apparent that by forming the tubes 28, which are in the hottest part of the furnace, relatively large, the tendency to produce dry spots therein is exceedingly small and their usefulness as supports is not impaired. The remaining tubes may be made smaller in the interest of a large area of heat absorbing surface without danger of overheating, as the large tubes 28 protect the smaller tubes from the radiant heat of combustion.

In the modified form of my invention shown in Fig. 3, the same desirable features of construction are present as are present in Figs. 1 and 2. In Fig. 3, however, I have shown a superheater 30 arranged within a space 31 provided between groups 21a and 22a of one of the sets of tubes 15a. The space 31 is provided by the arrangement of the tubes in the groups 21a and 22a and by omitting certain of these tubes. The superheater 30 is of the return bend tube type and is supported by plate members 32 carried by brackets 33 which are in turn secured to large, approximately straight tubes 34 (only one shown) connecting the water drum 14a with the upper steam and water drum 12a.

While I have shown my invention in only two forms, it will be obvious to those skilled in the art that it is not so limited but is susceptible of various other changes and modifications without departing from the spirit thereof, and I desire, therefore, that only such limitations shall be placed thereupon as are imposed by the prior art or as are specifically set forth in the appended claims.

I claim:

1. A water tube boiler comprising, in combination, means defining a combustion chamber for a furnace, a steam and water drum arranged at the upper part of the furnace and above the combustion chamber, a pair of lower water drums disposed at opposite sides of the combustion chamber and extending in the same general directions as the upper drum, a set of steam generating tubes connecting each lower water drum to the upper drum, each set being divided into first and second groups with the first groups being arranged adjacent and delineating the upper portions of the combustion chamber and the second groups being disposed remote from the combustion chamber and in the rear of the first groups with spaces provided therebetween, the tubes forming the first groups being formed straight for practically their entire length, the tubes forming the second groups being similarly bowed away from the combustion chamber so as to permit expansion and contraction thereof incident to temperature changes, a superheater disposed within the space between one of the second groups and the adjacent first group forming a set, each set of steam generating tubes constituting a single pass section with the furnace gases moving in a single direction from front to rear across the section and the tubes of

said first groups being of materially larger diameter than the tubes of the remaining groups whereby the tubes of the first groups constitute the main support for the steam and water drum 5 while the tubes of the other groups provide a predominating part of the entire steam generating surface, a gas outlet on each side of the drum, and gas distribution baffles each starting at an intermediate portion of one of said outlets and extending part way down over the rear tubes.

2. A boiler comprising in combination, means defining a combustion chamber of a furnace, a steam and water drum arranged at the upper 15 part of the furnace and above the combustion chamber, a pair of lower water drums disposed at opposite sides of the combustion chamber, sets of steam generating tubes connecting each lower water drum with the upper drum, each set being 20 divided into first, second and third groups with the first groups being arranged adjacent and delineating the upper portions of the combustion chamber and the second and third groups arranged at the rear of the first groups in the order 25 named, tubes forming the first groups being formed straight for practically their entire length, the tubes forming the second and third groups being bowed away from the combustion chamber so as to provide spaces between the first 30 and second groups and the second and third groups and so as to permit expansion and contraction incident to temperature changes, soot blowers disposed in the spaces between the first

and second groups, and the second and third groups, each set of steam generating tubes constituting a single pass section with the furnace gases moving in a single direction from front to rear across the section and the tubes of said first groups being of materially larger diameter than the tubes of the remaining groups whereby the tubes of the first groups constitute the main support for the steam and water drum while the tubes of the other groups provide a predominating part of the entire steam generating surface, a furnace gas outlet on each side of said drum, and gas distribution baffles each starting at an intermediate portion of an outlet and extending 10 part way down over the rear bowed tubes. 15

3. In a three-drum marine boiler, two submerged drums, an upper steam and water drum, a furnace, upwardly converging banks of steam generating tubes connecting the upper drum with the lower drums and arranged on opposite 20 sides of the furnace, the furnace gases being directed across each of said banks in a single pass, the tubes of said banks adjacent the furnace of large diameter and being substantially straight throughout the major portions of their lengths 25 while the remaining tubes of the banks rearwardly of the straight tubes are of materially smaller diameter and are curved throughout their entire lengths, a gas outlet on each side of the drum, and gas distribution baffles each starting 30 at an intermediate portion of a gas outlet and extending part way down over the rear tubes.

WILLIAM M. FIRSHING.
